UNITED STATES PATENT OFFICE

2,460,210

TOOLHOLDER

Braceell Barrett, Galena Park, Tex.

Application January 19, 1946, Serial No. 642,332

1 Claim. (Cl. 279—16)

1

This invention relates to a tool holder.

An object of the invention is to provide a tool holder of the character described specially adapted for use in connection with the operation of reamers, drills and similar tools, and which is of such construction that it will permit angular displacement of the tool so that it will perfectly line up with the work.

It is another object of the invention to provide a tool holder of the character described having a conventional shank adapted to be inserted into a standard type of machine spindle and having a floating adapter at the outer end of the shank to receive the tool to be used in the work, with a novel connecting and driving means between the shank and the adapter, which permits the adapter and tool to move angularly in relation to the shank so that the tool mounted on the adapter will follow the center line of a bore in the work, even though the center line of the bore may be in angular relation to the center line of the shank.

It is a further object of the invention to provide a tool holder of the character described of such construction that the tool mounted therein will be normally held in direct alignment with the shank.

With the above and other objects in view the invention has particular relation to certain novel features of construction, arrangement of parts and use, an example of which is given in this specification and illustrated in the accompanying drawings, wherein:

Figure 1 is a longitudinal sectional view of the holder.

Figure 2 is a fragmentary view of the shank, viewed on the line 2—2 of Figure 1.

Figure 3 is a cross sectional view taken on the line 3—3 of Figure 1.

Figure 4 is a cross sectional view taken on the line 4—4 of Figure 1.

Figure 5 is a cross sectional view taken on the line 5—5 of Figure 1, and

Figure 6 is an inner end view of the floating adapter.

Referring now more particularly to the drawings, wherein like numerals of reference designate the same parts in each of the figures, the numeral 1 designates a shank of conventional form and adapted to be inserted into the spindle of a standard machine.

On the outer end of the shank there is a hollow body 2, preferably formed integrally with the shank and of somewhat greater diameter than the diameter of the shank.

The outer end of the shank has a deep socket 3

2

which contains a coil pressure spring 4 and inserted into the socket 3, against said spring, there is a ball retainer 5, whose outer face has a concaved depression 6 in which the ball 7 is seated.

Mounted in the inner end of the body 2 there is a circular plate forming a floating driver 8 which has a central opening 9, in which the ball 7 is located. The floating driver 8 has opposed radial marginal grooves 10, 10. Drive pins 11, 11 are anchored to the bottom of the body and have enlarged circular heads located in the grooves 10, thus clutching the driver 8 with the body, for rotation therewith.

In the body there is a floating adapter 12 which has an external, annular, inwardly directed shoulder 13 and an outwardly tapering shoulder 14.

Surrounding the adapter, and interposed between the driver and the shoulder 13, there is a coil spring 15.

Screwed into the outer end of the body there is a gland 16 having an external, annular flange which abuts said end and whose inner end is tapered to conform to the taper of the shoulder 14.

Said tapering parts are normally held in abutting position by means of the spring 15 so that the adapter and the tool therein will be maintained in axial alignment with the shank.

The inner end of the adapter has a concave recess 17 to receive the ball 7 and also has the radial marginal slots 18, 18 at right angles to the grooves 10. There are the pins 19, 19 which are pressed into the driver 8 and which have enlarged circular heads which work in the slots 18 so as to clutch the driver with the floating adapter.

There is a slight clearance between the heads of the pins 19 and the slots 18 and also a slight clearance between the pins 19 and the slots 18 so as to give the tool holder the required amount of flexibility without the binding of parts.

Mounted on the outer end of the adapter there is a locking ring 20 which has an inside double cam-shaped groove 21 and opposite said groove, 45 through the wall of the adapter 12, there is an inwardly converging opening 22 in which a retaining ball 23 works. This ball may be inserted through an opening 24 in the locking ring 20 and retained therein by means of a plug 25 screwed 50 into said opening.

The outer end of the adapter is provided with a socket 26 for the reception of the shank of a reamer, or other tool. When the shank of said tool is inserted in the socket the locking ring 20 may be turned so as to cause the cam-

shaped bottom of the groove 21 to force the retaining ball 23 inwardly into the position shown in dotted lines in Figure 3, and into a recess in the tool shank so as to lock the tool in the adapter. In locking the tool in the adapter the locking ring may be turned in either direction, depending on the direction in which the tool and tool holder are to be rotated. When it is desired to release the tool from the adapter the locking ring 20 may be turned until the double cam-shaped groove 21 is centered relative to the opening 22 to allow the retaining ball 23 to move outwardly into the position shown in Figure 1, to release the tool shank so that the tool can be removed.

Normally the spring 15 will hold the adapter and tool in axial alignment with the holder shank 1 by holding the tapering shoulder 15 closely against the tapering seat of the gland so that the tool will properly align with the work; however, when the tool is applied to the work the pressure will unseat the tapering shoulder 14 from the tapering seat of the gland 16, the springs 4 and 15 yielding to permit this, and should the work not be precisely axially aligned with the machine spindle and shank 1 the adapter and tool will automatically align themselves with the central line of the bore being drilled, or reamed, by the tool, thus preventing inaccuracy in the work and without disengaging the operative connection between the shank 1 and the floating adapter 12.

The drawings and description are illustrative merely while the broad principle of the invention will be defined by the appended claim.

What I claim is:

A tool holder comprising, a shank whose outer end is formed with a hollow body of greater diameter than the shank, said shank being formed with a deep socket, a coil pressure spring in said socket, a ball retainer seated on the spring within said socket and whose outer face is formed with a concaved depression, a ball seated in the depression, a circular plate mounted within the body and forming a floating driver

which is provided with a central opening in which said ball is located, said driver having opposed radial marginal grooves, drive pins anchored to the bottom of the body and extending loosely into said grooves to clutch the driver with the body for rotation therewith, a floating adapter in the body provided with an outer end, tool-receiving, socket and with an external, annular, inwardly directed shoulder and an outer tapering shoulder, a coil spring around the adapter and interposed between the driver and the inwardly directed shoulder, a gland screwed into the outer end of the body and having an external annular flange which abuts said outer end and whose inner end is tapered to conform to the taper of said tapering shoulder, said spring around the adapter normally holding said tapering parts in contact, said adapter being provided with a concaved recess in its inner end to receive said ball and being provided with radial marginal slots at angles to said grooves, pins on the driver having heads which work loosely in said marginal slots to clutch the driver with the floating adapter, a locking ring on the body having an inside, double cam-shaped groove which converges into a central opening through the adapter and a ball retained in said double cam-shaped groove and working through the opening thereof.
